UNITED STATES PATENT OFFICE.

FRANK C. McCAFFREY, OF BURLINGTON, VERMONT.

ELECTRIC WHISTLE-BLOWING APPARATUS.

1,086,196.

Specification of Letters Patent.

Patented Feb. 3, 1914.

Application filed February 19, 1913. Serial No. 749,359.

To all whom it may concern:

Be it known that I, FRANK C. McCAFFREY, a citizen of the United States of America, and resident of Burlington, in the county of 5 Chittenden and State of Vermont, have invented certain new and useful Improvements in Electric Whistle-Blowing Apparatuses, of which the following is a full, clear, and exact description.

10 This invention has for its object to provide improved means for effecting the continuous operation of a whistle or other form of signal device, for a predetermined period, and to then throw it out of operation.

15 A further object of the invention is to cause one circuit to put another circuit in action, to advance a solenoid core, and operate a signal connected therewith; and to utilize a retarding device, such as a dash 20 pot to control the movement of said solenoid core.

In the drawings showing one embodiment of my invention, Figure 1 is an elevation of the apparatus; Fig. 2 is a section on line 25 2-2, Fig. 1; Fig. 3 shows the operating lever for the core. Fig. 4 shows the tripping levers, and Fig. 5 shows details of the dash pot control with the parts in different position.

30 The apparatus is shown as principally arranged in a casing 1, on a shelf 2 in which is suitably supported a coil 3 with which wires 71 and 72 are connected, comprised in a normally closed circuit of the fire alarm system. When this circuit is opened or interrupted by the turning in of an alarm, a lever 4 carrying an armature 72 for the coil, is released. The lever 4 swings on a pivot 5 and is connected with a spring 6 that draws 35 the lever 4 away from coil 3 when the circuit of the latter is broken. A second lever 8 connected with a spring 9, is swung on its pivot 90 toward lever 4 to engage a contact piece 10 on lever 8 with a contact piece 11

40 on lever 4; when lever 4 is released on opening of the circuit in coil 3 and swung by its spring 6 against a stop 91. One terminal wire 7 of an auxiliary circuit is attached to the lever 4, and when this lever is released 45 connecting pieces 10 and 11, the circuit is formed to lever 8. A wire 12 leads from lever 8 to a solenoid 13, from which a return wire 73 leads to the source of current for wire 7. The solenoid 13 is provided with a core 14 50 slidable therein, normally held out of the coil, and drawn into it when the solenoid

13 is energized. At the upper end of core 14 is shown a hook 15 connected with a plate 23 and a spring 22 around the hook holding the plate 23 away from the end of the core 60 frame 92 to provide a yielding connection between the core and the hook.

As shown in Fig. 3, a cable 16 connects hook 15 with one end of a lever 17 pivoted at 18, and having its other end connected by 65 a stiff spring 19 with a convenient part of the apparatus. This spring and lever serve to hold the core in the position shown and to retract it when in the coil 13. A cable 20 connects lever 17 with an arm 21 of a suitable whistle or other desired form of signal device, that will sound or operate as long as lever 17 is held depressed by the core 14. Attached to the lower end of the core 14 is a beveled block 24 so that when the core is 70 drawn downward, at the limit of its movement it will strike the beveled end of a lever 26. The latter has a shoulder 94 normally engaging a shoulder 95 on a lever 27 and is held in this position by a spring 28, 80 and the lever 27 has a spring 29 that will pull it downward when the block 24 shifts lever 26. As lever 27 is thus drawn downward when released from lever 26, it engages a hook 31 fast to a slide 32, that is 85 connected with a lever 33 swinging on a fixed pivot 30. A link 34 connects lever 33 with a lever 35 to pull the latter downward upon depression of lever 27 as described. A block 36 is suitably supported to slide and 90 is connected with lever 35. This block has an inclined face 37 which contacts with a similar inclined face 38 on the said lever 8, whereby when the block 36 is drawn downward by said levers this lever 8 will be 95 swung against the pull of its spring 9, causing a separation of the contact pieces 10 and 11, thereby effecting a rapid break of the circuit for the coil 13, through the wires 7 and 12.

100 A swinging latch 39 has a beveled lug 40 at its lower end which, when the block 36 is drawn downward, will engage a lug 41 carried by the block 36, serving to lock the block 36 in the depressed position, with the 105 terminals 10 and 11 separated. But when the coil 3 is again energized and attracts the lever 4, an arm 42 on the lever 4 will strike the lever 39 to disengage it from the lug 40, releasing the block 36. The latter 110 will be drawn upward by a spring 37; and a spring 74 will cause return of levers 35 and

33, and also of the hook 31 when spring 29 is restored. The resetting of the lever 27 within the lever 26 is caused by the engagement of the block 24 with a lever 44, connected with lever 27 by a link 45, it being understood that spring 29 will overbalance springs 74 and 37.

In order to regulate the return movement of the core 14 when drawn into the coil 13, I provide a suitable retarding device, such as a dash pot 56 having a piston 57 connected by a link 55 with a lever 54. A rod 50 is mounted on one side of the upper end of the core frame 92 and is connected with a coil spring 49 to return it when swung on its axis. The rod 50 has its lower end 51 inclined and projecting sidewise to engage a beveled lug 52 carried by a slide 53 that is connected with the lever 54. When the core 14 has been drawn down, and the circuit is broken by the described means, and the lever 17 draws the core up again, the lug 51 will engage with the lug 52 on the slide 53 to draw the slide upward. This will swing lever 54 and cause the piston 57 to be drawn out of the dash pot, thereby creating a retarding force and causing a slow return of the core 14. At the latter part of this movement a rod 59 engages a lever 60 carrying a valve 61 normally closing an opening 62 in the dash pot, whereby air is admitted thereto. A beveled lug 63 on the frame engages the lug 51 on the rod 50 and swings the latter to release the lug 52 of the slide 53. A spring 58 connected with lever 54 is extended when the lever is swung as just described, and serves to return the piston 56 and also slide 53 to normal position. The rod 59, whose head 64 serves to swing the lever 60, is adjustably connected with the lever 54 by a nut 65, so that the lever 60 can be operated at the desired period in the return of the core.

The operation of the device is as follows: The circuit for the coil 3 is normally closed, but opened when an alarm is turned in. The lever 4 will, therefore, be normally attracted to disconnect the terminals 10 and 11 thereby cutting out the coil 13. When the lever 4 is released by the coil 3 being de-energized, the circuit is closed for the coil 13. The coil 13 will now draw the core 14, so that the lever 17 will swing the arm for the whistle, which it will be understood will continue to sound until the core 14 again returns to normal position. When the core 14 reaches the lower limit it will swing levers 33 and 35, depressing block 36, that will shift the lever 8 to break the circuit at the terminals 10 and 11, thereby cutting out the coil 13. The core 14 is now free to rise, being returned by the spring 19; but this movement is controlled by the dash pot 56 and its controlling means as has been described. At the latter portion of the return

movement of the core the dash pot and connected parts are restored, and the several levers will return to normal position. The block 24 raises lever 27 and resets it on shoulder 94 of lever 26. But it will be understood that the lever 8 which has been swung to break the terminals 10 and 11 is locked in such position and cannot return until circuit is again established in the coil 3. By this means the whistle or alarm will continue to sound during the entire period in which the core 14 is drawn downward and is retracted under the control of the dash pot. The next reenergizing of the circuit in the coil 3 will attract the armature 72 and lever 4 against spring 6, and the latch will release block 36 that will return to normal position through its spring 37, thereby allowing lever 8 also to return to normal position through the inclined faces 37 and 38.

I claim:

1. The combination in an electric alarm, with a normally closed circuit that is opened to send the signal, of an electromagnet in said circuit, an armature swung by the magnet, a circuit including a solenoid, a core operated by said solenoid, an alarm connected with said core to be operated when the core is drawn into the solenoid from normal position, a pair of contacts in the circuit for the solenoid one of which is carried by said armature and thereby separated from the other when the armature is attracted by the magnet, a spring for shifting the armature to connect said contacts when the circuit is broken for the magnet, means controlled by said core for separating said contacts when the core has been drawn into the solenoid to its limit of movement to permit the core to return to normal position, said means maintaining the circuit for the solenoid open until the magnet is again energized.

2. The combination in an electric alarm, with a normally closed circuit that is opened to send the signal, of an electromagnet in said circuit, an armature swung by the magnet, a circuit including a solenoid, a core operated by said solenoid, an alarm connected with said core to be operated when the core is drawn into the solenoid from normal position, a pair of contacts in the circuit for the solenoid one of which is carried by said armature and thereby separated from the other when the armature is attracted by the magnet, a spring for shifting the armature to connect said contacts when the circuit is broken for the magnet, means connected with said core for separating said contacts when the core has been drawn into the solenoid to its limit of movement to permit the core to return to normal position, said means maintaining the circuit for the solenoid open until the magnet is again energized, and a retarding device for controlling the return movement of the core.

- lever when advanced, a spring holding said lever against said slide, a contact piece on the armature arranged to engage said contact piece on the lever in the normal position of the lever when the armature is moved against its stop by its spring, a circuit including a solenoid, that is closed by said contact pieces when engaged, a core operated by said solenoid, a signal device actuated by said core, means controlled by said core when advanced by its solenoid to shift said slide and swing the lever to separate the contact pieces at the limit of movement of the core, thereby permitting the core to return to normal position, and a latch arranged to retain the slide in advanced position until the magnet is again energized, and an arm on the armature arranged to trip the latch when the armature is again energized.
9. The combination in an electric alarm, with a normally closed circuit that is opened to send the signal, of an electromagnet in said circuit, an armature pivotally mounted to be swung by the magnet, a stop for the armature, a spring for retracting the armature against the stop when the circuit is broken, a swinging lever carrying a contact piece, a slide arranged to swing said lever when advanced, a spring holding said lever against said slide, a contact piece on the armature arranged to engage said contact piece on the lever in the normal position of the lever when the armature is moved against its stop by its spring, a circuit including a solenoid that is closed by said contact pieces when engaged, a core operated by said solenoid, a signal device actuated by said core, means controlled by said core when advanced by its solenoid to shift said slide and swing the lever to separate the contact pieces at the limit of movement of the core, thereby permitting the core to return to normal position, and a latch arranged to retain the slide in advanced position until the magnet is again energized, and an arm on the armature arranged to trip the latch when the armature is again energized.
10. The combination in an electric alarm with a normally closed circuit which is open to send the signal, of an electromagnet in said circuit, an armature swung by the magnet, a circuit including a solenoid, a core operated by said solenoid for operating an alarm when the core has been drawn into the solenoid, a lever connected with the circuit of the solenoid, a contact on the lever, a contact on the armature, said armature being connected with the circuit for the solenoid whereby the circuit is made and broken by the said contacts on movement of the armature and of the lever, a spring for moving the armature away from the magnet, a stop for the armature, a spring on said lever for moving it toward the armature to engage said contacts, the armature being shifted by the magnet when moved to open said contacts in the normal position of said lever and to close the contacts when the magnet is open to thereby close the circuit of said solenoid, a slide operatively connected with the said core to be shifted at the limit of movement of the core, means connecting the slide and said lever to shift the lever away from position of engagement with the armature contact, a latch for holding the slide and lever in said shifted position, and means connected with the armature for tripping said latch when the armature is shifted by attraction from the magnet.
11. The combination in an electric alarm of an electromagnet in the sending circuit, an armature for the magnet, a circuit including a solenoid, a circuit breaker operated by said armature for controlling the solenoid, a core operated by the solenoid for actuating an alarm, a dashpot, a lever controlled by the dashpot piston, a slidable rod connected with said lever, and means connected with said core for engagement with said rod on the return movement of the core to retard such return movement.
